US00D516686S

(12) **United States Design Patent** (10) Patent No.: **US D516,686 S**
Wilk, Jr. et al. (45) Date of Patent: **** Mar. 7, 2006**

(54) **TEE COUPLING**

(75) Inventors: **Charles E. Wilk, Jr.**, Northampton, PA (US); **Anthony J. Cuvo**, Coopersburg, PA (US); **Jianyong Sun**, Macungie, PA (US)

(73) Assignee: **Victaulic Company**, Easton, PA (US)

(**) Term: **14 Years**

(21) Appl. No.: **29/211,753**

(22) Filed: **Aug. 20, 2004**

(51) LOC (8) Cl. **23-01**

(52) U.S. Cl. **D23/262**

(58) Field of Classification Search D23/262, D23/263, 259; 285/133.11, 133.3, 133.21, 285/133.4-133.6

See application file for complete search history.

(57) **CLAIM**

The ornamental design for a tee coupling, as shown and described.

DESCRIPTION

FIG. 1 is a perspective view of a first embodiment of our design for a tee coupling;

FIG. 2 is a left side view of the tee coupling shown in FIG. 1, the right side being shown in perspective in FIG. 1;

FIG. 3 is an end view of the tee coupling shown in FIG. 1,

the opposite end view being identical;

FIG. 4 is a bottom view of the tee coupling shown in FIG. 1;

FIG. 5 is a top view of the tee coupling shown in FIG. 1;

FIG. 6 is a perspective view of a second embodiment of our design for a tee coupling;

FIG. 7 is a left side view of the tee coupling shown in FIG.

6, the right side being shown in perspective in FIG. 6;

FIG. 8 is an end view of the tee coupling shown in FIG. 6,

the opposite end view being identical;

FIG. 9 is a bottom view of the tee coupling shown in FIG.

6; and,

FIG. 10 is a top view of the tee coupling shown in FIG. 6.

The broken lines shown in the various Figures are for illustrative purposes only and form no part of the claimed design.
